CLAIM

The ornamental design for a display screen with a graphical user interface, as shown and described.

DESCRIPTION

FIG. 1 is a front view of a display screen with graphical user interface;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof;

FIG. 7 is a front view of a seventh embodiment thereof; and,

FIG. 8 is a front view of an eighth embodiment thereof.

The broken line showing of the display screen forms no part of the claimed design. The broken line showing the remainder of the graphical user interface forms no part of the claimed design.

1 Claim, 8 Drawing Sheets
